DESIGN FOR A COMBINED KNIFE AND HONE HOLSTER

Tracy W. Smith, Gastonia, N. C.

Application April 10, 1945, Serial No. 118,941

Term of patent 7 years

(Cl. D22—6)

To all whom it may concern:

Be it known that I, Tracy W. Smith, a citizen of the United States, residing at Gastonia, in the county of Gaston and State of North Carolina, have invented a new, original, and ornamental Design for a Combined Knife and Hone Holster, of which the following is a specification, reference being had to the accompanying drawing, forming a part thereof.

I claim:

The ornamental design for a combined knife and hone holster, as shown.

TRACY W. SMITH.
